Edmund L. Izzi, Cleveland, and Edgar B. Karns, Rocky River, Ohio, assignors to Westinghouse Electric Corporation, East Pittsburgh, Pa., a corporation of Pennsylvania

Application May 29, 1958, Serial No. 51,120

Term of patent 14 years

(Cl. D48—31)

The side of the luminaire not shown is the same in appearance as the side shown.

The dominant features of our design reside in the portions shown in full lines.

We claim:

The ornamental design for a luminaire, substantially as shown and described.
